J. REID.
FURNACE FRONT.
APPLICATION FILED NOV. 2, 1918.

Patented Oct. 7, 1919.

2 SHEETS—SHEET 2.

UNITED STATES PATENT OFFICE.

JOHN REID, OF NEW YORK, N. Y.

FURNACE-FRONT.

1,318,331.

Specification of Letters Patent.

Patented Oct. 7, 1919.

Application filed November 2, 1918. Serial No. 260,884.

To all whom it may concern:

Be it known that I, JOHN REID, a subject of the King of Great Britain, and residing at 30 Church street, in the city of New York, 5 in the State of New York, in the United States of America, have invented a new and useful Improvement in Furnace-Fronts, of which the following is the specification.

The invention relates to improvements in 10 furnace fronts as described in the present specification and illustrated in the accompanying drawings that form part of the same.

The invention consists essentially of the 15 novel construction and arrangement of parts, whereby the casting is facilitated and the sections and pieces of the front made so as to be adaptable to standardization.

The objects of the invention are to eliminate 20 the expense and inconvenience incidental to making each front special and to provide in spite of the variations called for by differences in the furnace diameters and flangings, by variations in fuel systems, oil 25 or coal fuel equipment, by combinations of both or from any other reason arising from special conditions of sale, all or many of the sections or parts of the front from a stock in hand, to simplify casting processes, 30 to cut out lost casings, which are quite intricate in the ordinary solid cast fronts, to reduce losses in foundry work by eliminating waste in material and labor, and generally to apply an "efficiency system" in the 35 production of furnace fronts.

In the drawings, Figure 1 is a front elevation of the front plate.

Fig. 2 is a rear elevation of the back plate.

40 Fig. 3 is a mid-cross sectional view through the fuel and air passage casings and ash pit flare, showing an outline of the back plate.

Fig. 4 is a cross sectional view of the complete 45 furnace front on the line 4-4 of Fig. 3.

Fig. 5 is a cross sectional view of the complete furnace front on the line 5-5 of Fig. 3.

50 Fig. 6 is a vertical mid-sectional view of the assembled parts.

Like numerals of reference indicate corresponding parts in each figure.

In further explanation of the purpose to 55 standardize the construction of forced draft furnace fronts for Scotch and other

forms of steam boiler, as referred to in my Patent No. 1,300,876, it may be said that in this invention a new form is developed, which will greatly facilitate the construction, manufacture and marketing of the article.

It will be understood from the description herein that I can order cast a large number of the front plates with their attachments 60 and mounting such as coaling doors, ashpit doors, latches, handles, cover plates, clips and other pieces and assemble the same and put them into stock. I can also have cast a corresponding number of what I call the 65 intermediate castings with air chambers, also the ashpit wall castings, which will go between the front and back plates at their bottom peripheries to constitute the bottom of the ashpit passage.

70 On receiving an order for a certain number of fronts of specified diameter to suit specified furnace diameter and flanging, I cast only the back plates to order and assemble them by bolting the intermediate 75 casting, ashpit bottom casting and front plate to complete the furnace front.

Care must, of course, be taken in making the resulting bolted front as substantial 80 when assembled as the ordinary form of single casting, but this presents no difficulty to a practical man as a good asbestos or other form of cement may be used to stop the joints, where air leaks might occur or stresses in the casting develop from unequal strain of the bolts.

It will be noted also that where repairs 85 have to be effected or breakages made good, one part or another in each front will have to be discarded, instead of a whole solid cast front as at present, thus greatly reducing losses in shipment or by damage on ship board. Parts most affected by breaking in service are the back plates, of which a spare supply can be carried.

100 Referring to the drawings, the front plate 1 forms one of the main parts making up this invention and is preferably cast as a separate piece or section of the front, though not necessarily as it may be cast with the fuel passage.

105 The front plate 1 is thus made standard and within reason applied to all furnaces of the type, for which these fronts are designed. This plate 1 is formed with the ashpit opening 2, the door opening 3 and the air valve opening 4 above said door opening 3,

which is centrally arranged above the said ashpit opening 2.

From the inner surface of the said front plate, around the lower portion of the fuel opening and near to the edge, a substantially U-shaped rib or ledge 5 projects inwardly as a support for the fuel passage casing. Above the said door opening, the central boss 6 projects inwardly and at each side of said door opening, the bosses 7 and 8 also project inwardly, these bosses being so arranged for the purposes of centering and alining the parts in assembling and preventing displacement due to varying temperatures after installation.

On the face of the front plate 1, the usual hinge lugs 9 are formed at the side of the door opening 3. The arc-shaped rib or ledge 10 is formed on the inner side of said front plate close to the bottom edge, to support the ash pit plate flare, and around the said ash pit opening 2 the plate 1 is thickened to form a frame and a seat 11 for the ash pit door.

25 The casing 12 forms the fuel passage and the upper portion 16 is inclosed by the wall 17 and forms therewith the air chamber 13, having the inlets 14 through the top wall thereof and the outlets 15 through the back plate. It will be seen that the upper part 16 of the fuel casing 12 forms the inner wall of the air chamber 13 and that the wall 17 forms the outer inclosure, the latter joining the casing 12 at the lower end of the part 30 indicated by the numeral 16, thereby forming a bottom wall 17^a to said chamber 13, which stands on the extremities of the U-shaped ledge 5.

At the rear end of the wall 17, the joint 40 recess 20 is formed to receive the back plate and similarly at the rear end of the wall 12, the joint recess 19 is formed, being the lower portion of the fuel casing. The rib 21 from the front plate provides a joint recess for 45 the front end of the wall 17.

The bosses 6, 7 and 8 extend into the air chamber 13 between the walls thereof in the front of said air chamber 13 and aid in maintaining the fuel passage casing in a 50 fixed position.

All the ledges and ribs are integral with the main castings.

The bolt lugs 22 extend from the upper outer wall 17 of the casing 12 and the bolt lugs 23 from the lower single wall 12.

The fuel passage casing 12 is preferably a standard part or section, therefore applicable to the numerous furnace fronts of the chosen type.

60 The back plate 24 may be made in many different sizes and forms, though it is always possible to stock a considerable quantity of each of the different patterns, thereby gaining one of the objects of my invention.

65 This advantage of having a number in stock

is greatly facilitated by the use of my adapter ring as described in my Patent No. 1,300,876.

The back plate 24 is formed to receive the ash pit flare in the joint recess formed by 70 the rib or ledge 25 and on the rear side an annular flange 26 projects and is reinforced behind said rib 25. The ash pit opening 27 is made in the plate 24 below the fuel opening 28, the latter receiving the fuel passage 75 walls in the joint recesses prepared therefor.

The ash pit flare 29 having the lugs 30 and end flanges 31 rests on the ribs 10 and 25 and is secured between the front plate 1 and the back plate 24 and is flush with the 80 openings 2 and 27.

The front plate 1, the fuel casing 12, the ash pit flare 29 and the back plate 24 are all held together by the various bolts 32 and preferably asbestos cement is used in the 85 joint recesses to effectually close any openings that may occur due to strain or stress in assembling or possible inequalities in the castings.

The several parts rigidly secured together 90 constitute the furnace front complete, unless an adapter ring is required to fit it to the furnace mouth.

The accessories, such as the doors, hinges, catches, fastenings and valves are fitted to 95 their positions and may all be of standard design. The back plate and the ash pit flare may be readily replaced at any time and as before explained, it is particularly desirable to have a replaceable back plate.

100 It will thus be seen that the remarks hereinbefore setting forth the advantages of the invention are justified by the detailed description of the parts, and that the furnace front may readily be formed in two or more sections or pieces and thereby make it possible to standardize one or more of said sections or pieces and by so doing increase the reliability and life of the furnace front and facilitate the replacing and repairing of 110 parts.

Various changes may be made in the construction of this device without departing from the spirit of the invention so long as they remain within the scope of the claims 115 for novelty following.

What I claim is:—

1. A furnace front comprising a front plate, a back plate, a fuel passage casing and an ash pit flare, said casing and ash pit flare 120 being interposed between the front and back plates, bosses formed on one of the plates and adapted to guide the casing to its operative position in assembling the parts, and ledges carried by the said plates for receiving and supporting the ash pit flare.

2. A furnace front comprising a front plate having guiding bosses and provided with a fuel opening, a substantially U-shaped ledge carried by the front plate at 130

the inner face thereof and extending around the lower portion of the fuel opening, forming upright and horizontal supports, an arc-shaped ledge also carried by the front plate 5 and located adjacent to the lower edge thereof, a fuel passage casing having an air chamber and supported on said U-shaped ledge, the said bosses being adapted to guide the casing to its operative position in assembling 10 the parts, and the said upright supports abutting the lower wall of the air chamber of the said casing and the said air chamber receiving the said guiding bosses of the front plate, an ash pit flare arranged upon the arc-shaped ledge, a back plate formed to 15 fit the rear end of the said fuel passage casing and provided with means for supporting the ash pit flare, and bolts rigidly securing the said parts together.

Signed at New York city this 29th day of 20 October, 1918.

JOHN REID.
